DIETARY SUPPLEMENT BLOCK FOR CATTLE

Charles F. Aniser, King City, Mo.

Filed May 19, 1961, Ser. No. 65,235

Term of patent 14 years

(Cl. D12—2)

I claim:

The ornamental design for a dietary supplement block for cattle, as shown.
